(57) **CLAIM**

The ornamental design for a fiber optic cable bracket, as shown and described.

DESCRIPTION

FIG. 1 is an environmental perspective view, illustrating a fiber optic cable bracket with fiber optic cables mounted in the bracket;

FIG. 2 is a perspective view thereof;

FIG. 3 is a top elevation view thereof;

FIG. 4 is a bottom elevation view thereof;

FIG. 5 is a right-side elevation view thereof;

FIG. 6 is a left-side elevation view thereof;

FIG. 7 is a back side elevation view thereof; and,

FIG. 8 is a front side elevation view thereof.

The broken lines in the drawings depict portions of the fiber optic cable bracket that form no part of the claimed design.
